METHOD FOR THE OXIDATION OF
BLACK LIQUOR

Adalberto Tirado, Tlaipam, Mexico City, Mexico, assignor

City, Mexico, a Mexican corporation

Filed Mar. 2, 1961, Ser. No. 92,839
4 Claims. (Cl. 23—48)

This invention relates to a method of and apparatus for the oxidation of sulphur compounds in solution, especially so-called black liquors, which contain sulfides and mercaptans or other sulphur-containing compounds, such as are formed in the course of paper pulp making and in petroleum refining.

The invention will be herein illustrated particularly in connection with the oxidation of sulphur compounds obtained in making paper pulp.

It is customary practice in pulp and paper making, to evaporate and dry such black liquors, and finally to calcine the dry product in order to recover, in as high a proportion as possible, the soda and sulphur, for re-use in the pulp cooking process. As is well known, however, a substantial quantity of sulphur is lost in the form of hydrogen sulfide, mercaptans, or other organic sulphur compounds, during the evaporation or drying and calcination. Moreover, the escape of these compounds is objectionable because of their malodorous properties. Consequently, it has heretofore been the practice to oxidize the sulphur compounds in order to convert them into compounds exhibiting lower volatility, thereby decreasing both the sulphur losses and the malodors.

To that end, it has heretofore been the conventional practice to oxidize the black liquors in tanks or towers at normal atmospheric pressure, the oxidation being performed by scrubbing the liquor with air. Normally, air is added in a ratio of 100 volumes of air to 1 volume of liquor. Under these conditions, most of the sodium sulfide is converted into sodium thiosulfate, the conversion of the sodium sulfide ranging from about 50 to 100%, even though conversion of sodium sulfide into sodium thiosulfate theoretically requires about 1.5 liters of air per gram of sodium sulfide. Thus, liquor normally containing 5 to 10 grams sodium sulfide per liter should require only about 8 to 15 liters of air per liter of liquor. It will be seen, therefore, that the quantity of air utilized in the conventional practice of oxidizing black liquor amounts to about 6 to 12 times the theoretical requirement.

Furthermore, I have found that the oxidation of mercaptans, organic sulfides and disulfides is more difficult to obtain than the oxidation of sodium sulfide. Consequently, a substantial portion of mercaptans and organic sulfides and disulfides remains in the liquor after it has been subjected to the conventional procedure for oxidation with air at atmospheric pressure, as set forth above. It has been determined that no more than about 10 to 50% of the mercaptans is oxidized under such conditions. Yet it is the mercaptans and organic sulfides and disulfides which are the principal components that cause malodorous air pollution in the operation of kraft pulp mills.

Moreover, the conventional practice of oxidation as above set forth also requires, in order to promote contact between the air and the black liquor, the use of towers which either contain packing material or which are provided with a series of perforated trays.

The principal object of the present invention is to improve the efficiency of the oxidation of sulphur compounds in solution, especially black liquors containing sodium sulfide, mercaptans, and organic sulfides or disulfides.

2

It is a more particular object of the invention to provide a process for the oxidation of such sulphur compounds in solution, capable of operating so as to effect a substantially complete oxidation of sodium sulfide and to effect oxidation of mercaptans to the extent of from 50 to 100% thereof, in contrast to the 10 to 50% oxidation of mercaptans obtained in the conventional practice.

Several analytical methods are used to determine the degree or efficiency of such oxidation. The most widely used analytical methods are (1) the colorimetric method (Standard Procedure, British Columbia Forest Products, Crofton); (2) the potentiometric method (Borlew and Pascoe, T.A.P.P.I., Suggested Method, Tech. Assoc. Papers 30: 570-572, June 1947), and (3) the conventional iodine method. Since the colorimetric method determines only sodium sulfide, while the potentiometric method determines sodium sulfide plus mercaptans, and the iodine method measures sodium sulfide, mercaptans, organic sulfides, organic disulfides and other reducing compounds, it is a relatively simple matter to calculate the efficiency of the oxidation of at least the sodium sulfide and the mercaptans, when they are considered separately.

Another object of the invention is to provide a method for the oxidation of sulphur compounds in solution, as above mentioned, without requiring the use of treating towers containing the conventional packing material or series of perforated plates or trays for promoting the contact between air and the liquor.

Other objects and advantages of the invention will hereinafter appear, or will be apparent to those skilled in the art, from the following specifications taken in conjunction with the accompanying drawing, the single figure of which illustrates diagrammatically, an arrangement of apparatus that may be utilized in the practice of the invention.

Briefly stated, the objects of the invention may be achieved by subjecting the sulphur compounds in solution, such as black liquor, to oxidation by treating the same with air at super-atmospheric pressures of the order of 10 to 100 pounds per square inch while maintaining the solution at temperatures in the range of from about 70° to, say, 220° F., the higher the temperature and pressure, the better the result being. Within this relatively broad range of temperature and pressure, operating temperatures of the order of 100 to 180° F. and pressures of the order of 25 to 75 pounds per square inch are to be preferred in most instances.

More specifically, the oxidation is particularly advantageous when performed at a temperature of the order of 140° F. and a pressure of about 50 pounds per square inch, since under these conditions, the volume of air utilized may be greatly reduced, it being sufficient to use 2 or 3 times the theoretical value, instead of 6 to 12 times the same, and amounting to only 20 to 40% of the air normally used when the oxidation is performed at atmospheric pressure. At the same time, the oxidation of sodium sulfide and mercaptans remains as high as 95 to 100%. Under these conditions, also, apparently, the oxidation of organic sulfides and disulfides is also very high.

Moreover, these results may be obtained in the practice of the invention without requiring the use of the conventional series of perforated trays or plates, or of packing material, in the treating towers, to promote contact between the air and the liquor. Thus, the benefits of the invention may be attained by merely leading the air through one or several simple wire mesh diffusers into the bottom of an empty tank, pipe, or reactor, into the bottom of which the liquor is introduced.

At any rate, by carrying on the oxidation of the sulphur compounds in solution under super-atmospheric

pressure in accordance with the invention, the improved efficiency of oxidation and the other advantages mentioned are obtained, owing evidently to the increased partial pressure and solubility of the oxygen.

As illustrative of the efficiency of oxidation of the sulphur compounds in black liquor, obtainable by the practice of the invention, several examples showing the percentage of oxidation of mercaptans under varying conditions of temperature and pressure are set forth in the following tabulation.

	Temperature (degrees C.)	Pressure (lb./sq. in.)	Percent Oxidation of Mer- captans
1	20	25	66
2	20	50	72
3	20	75	80
4	65	50	100

Referring to the accompanying drawing, wherein is diagrammatically shown one form of a reactor and its connections for carrying out the oxidation of black liquor obtained in the operation of pulp mills, the reference numeral 1 designates the reactor. Hot black liquor may be pumped into the reactor through a liquor inlet pipe 2, while compressed air is introduced through an inlet pipe 3, so that a pressure of 10 to 100 pounds per square inch, and temperatures of 70° to 220° F. may be maintained in the reactor. One or more wire mesh diffusers, as indicated at 4, are preferably arranged adjacent the bottom of the reactor and connected with the air inlet pipe 3, in order to assist in mixing the air with the liquor. An automatic pressure relief valve 5, of any suitable construction, is provided on top of the reactor, in order to keep a constant pressure in the reactor and to allow the mixture of oxidized liquor and excess air to discharge through outlet 6.

In the practice of the process, a reaction time or retention time in the reactor amounting to about 2 to 4 minutes is sufficient for the air to oxidize the sodium sulfide, mercaptans and organic sulfides or disulfides.

As will be evident from the foregoing description, the invention may find a variety of embodiments and applications in addition to those specific illustrations which have hereinabove been set forth.

What I claim is:

1. The process of treating black liquors obtained in the production of paper-making pulp and containing sodium

sulphide and malodorous organic sulphides, disulphides and mercaptans, which consists essentially of oxidizing said malodorous constituents of the black liquor to convert them into non-malodorous compounds, said oxidation being effected by non-catalytically treating said black liquor with air at superatmospheric pressures in the range of from 10 to 100 pounds per square inch while maintaining the same at a temperature in the range of from 70° to 220° F., said treatment with air being effected by diffusing compressed air into said liquor while feeding the liquor and the compressed air into one end of a reaction zone in which a substantially constant pressure within said range is maintained, and discharging from the opposite end of said zone the thus oxidized liquor containing the non-malodorous oxidation products of said sulphides, disulphides and mercaptans mixed within excess air.

5 2. The process as defined in claim 1, wherein the pressure maintained in said zone is in the range of 25 to 75 pounds per square inch super-atmospheric, and wherein

20 said temperature is in the range of 100° to 180° F.

25 3. The process as defined in claim 1, wherein the pressure maintained in said zone is about 50 pounds per square inch super-atmospheric, and wherein said temperature is of the order of 140° F.

25 4. The process as defined in claim 1, wherein the retention time of said liquor in said zone is in the range of 2 to 4 minutes.
